DESCRIPTION

FIG. 1 is a perspective view of an orthopedic device, showing our design.

FIG. 2 is a first side elevational view of the orthopedic device shown in FIG. 1.

FIG. 3 is a second side elevational view of the orthopedic device shown in FIG. 1.

FIG. 4 is a front elevational view of the orthopedic device shown in FIG. 1.

FIG. 5 is a rear elevational view of the orthopedic device shown in FIG. 1.

FIG. 6 is a top plan view of the orthopedic device shown in FIG. 1; and,

FIG. 7 is a bottom plan view of the orthopedic device shown in FIG. 1.

The broken lines illustrate environmental structure and form no part of the claimed design.
